RECEPTACLE LOCK

Earl W. Storms, Los Angeles, Calif.

Application July 20, 1931. Serial No. 551,865

1 Claim. (Cl. 232—41)

My invention relates to improvements in receptacle locks, wherein the operation of an outer door is controlled by the operation of an inner door and more particularly in which an improved locking mechanism is provided for automatically locking an outside door closed only after said door has been opened and closed following an opening and closing movement of an inner door. A further feature of my improvement is the releasing of an outer door by said locking mechanism immediately when the inside door is opened, said outer door remaining released until the outer door has been subsequently closed following a complete opening and closing movement of the inner door.

An object of my invention is to provide locking mechanism of the class stated which is particularly adapted for protecting built in article receptacles for dwellings and other places, against pilfering, whereby milk containers, parcels and other articles may be deposited without risk from theft, the outer door being closed and locked and not again released until the attendant has opened the inside door. Among further objects are simplicity of construction and greater effectiveness in use.

More particularly this invention is an improvement upon the structure disclosed in my prior patent, Number 1,219,360, granted to me on the 13th day of May, 1917.

In the accompanying drawings forming part of this specification, Fig. 1 is a horizontal section of an article receptacle showing my improved locking mechanism applied thereto, said article receptacle being illustrated built into a portion of a wall structure and the housing of the locking mechanism being partly broken away and in section; Figs. 2, 3 and 4 are perspective views of my improved locking mechanism, parts of the locking mechanism housing being broken away and in section and details of the article receptacle and its doors being shown in section, Fig. 2 showing the outer door closed and the inner door open, Fig. 3 showing the outer door open and the inner door closed, and Fig. 4 showing both the outer and inner doors closed; and Fig. 5 is a horizontal section of a detail of the article receptacle showing the locking mechanism housing partly broken away and in section and the outer and inner doors closed, my improved locking mechanism being illustrated with the latch member and its gate block pressed back by the catch on the outer door and said latch being illustrated in a position to turn horizontally into normal position and engagement with the catch on the outer door.

As shown in the drawings the several parts of the locking mechanism are attached to a small housing A, which in turn is fastened to the inner walls of the article receiving receptacle B (see Fig. 1), by screws 10 or other suitable means, said receptacle being built into a wall C of a dwelling or other structure and provided with outer and inner hinged doors D and E. These doors are provided with ordinary spring fasteners 11 and 12 by which they are releasably held closed but not locked so that a delivery of articles may be made from the outside and said articles readily removed from the inside of a dwelling and the doors closed and kept closed. Said housing has top, bottom and side walls 13, 14 and 15 and end walls 16 and 17 to which the parts of the locking mechanism are attached in the following manner.

The locking mechanism contained in said housing A and by which the outer door is locked after a delivery is made and not again unlocked except through the operation of the inner door, consists of the following parts. F is a latch formed by a two part lever having a main supporting member 18 and a catch engaging member G, said supporting member being pivoted by shaft 19 to tilt up and down in a yoke 20 which is secured to the top wall 13 of the housing by screws 21. One end of said lever has a gauge 22 which swings freely between the wall 17 and stop 23 on a reciprocable lock actuating shaft 34, to be hereinafter described, to limit the swinging movement of the inner opposite end 24 of said lever between horizontal or normal position as shown in Figs. 3 and 4 and downwardly tilted unlocking position as shown in Fig. 2. The catch engaging member G is mounted to swing laterally by a bolt 25 on the inner end 24 of the main supporting member 18 of lever F and is adapted to swing laterally. Member G has a hook 26 on its forward end in juxtaposition to opening 27 through the end 16 of the housing and said hook in turn has a curved forward edge 28 which acts as a guide to deflect and cause the catch engaging member G of the lever to swing laterally into engagement with a rigid catch H resembling a down turned hook mounted upon the inner face of the outer door D and adapted to enter the catch receiving opening 27 when said door is closed. The catch engaging member G constituting part of the latch F is urged horizontally into vertical alignment with the catch receiving opening 27 by a leaf spring 30 mounted upon yoke 20. In this position a block member F' to be hereinafter described, presses against the inner surface of the side wall 15 of the housing to limit the movement of catch en-

gaging member G under the action of said spring.

The latch F is urged upwardly into horizontal position with its catch engaging member G in catch engaging or "normal" position and in juxtaposition to opening 27, by a retractile spring 32 which is secured to the gauge 22 and a rigid abutment 33 on the bottom wall 14 of the housing. In this position the stop shoulders 37 and 38 on catch engaging member G slidably contacts with the inner face of the upper wall 13 to define the "normal" position of and assist in guiding member G in part of its movement. The reciprocable shaft 34 constituting part of the depressible lock actuator slides freely through and is guided by the rigid abutment 33 and the end wall 17 of the housing, its inner end projecting through said abutment and being limited in inward movement by a stop 35, on the bottom wall of the housing and having its outer end projecting through the inner doorway in position to be forced into its innermost position to swing the latch member into "normal" position by the closing movement of the inner door E. A compression spring 36 between the shoulder piece 23 on the shaft and the abutment 33 normally urges the shaft into outermost depressible position with the gauge 22 striking against the wall 17 of the housing and the latch F tilted down out of engagement with catch H.

It will be noted that the expansive strength of compression spring 36 is greater than the pulling tendency of retractile spring 32 so that latch F is swung down when the door E is opened and the lock actuator released into outermost position but is drawn upward into "normal" position by spring 32 when shaft 34 is moved into depressed position by the closing movement of door E.

Arranged on the latch member G is a block member F' whose function is to obstruct entrance to the throat 39 (see Fig. 5) of the latch member G by catch H, when the inner door is closed after the closing of the outer door. This block F' is slidably mounted to reciprocate freely longitudinally on the latch member G and normally is urged outwardly in obstructing position by a longitudinal shaft 40, mounted on a support 41 struck upwardly from the block and slidably supported through the stop shoulders 37 and 38 on the latch. An expansion spring 42 encompassing shaft 40 between shoulder 38 and a stop 43 on said shaft depressibly urges the block into normal blocking position but permits catch H to slide the block so that it will automatically engage the latch when the outer door is closed and when the inner door is open.

Operation

Assuming that both of the doors are closed (see

Fig. 1), following a delivery of articles into the receptacle from outside, the catch H is engaged by the member G of latch F, thus holding the outer door locked closed. When the inner door is opened to remove articles from the receptacle the door operated lock actuator 34 is released into outermost position (see Fig. 2) and the latch is tilted down and released from engagement with catch H, in which position the outer door is left free to be opened for another delivery. When the inside door is closed and the lock actuator 34 depressed, the latch is prevented from again engaging catch H by the block F', which automatically prevents the latch swinging up by striking the lower down turned end of the catch. Thus the outer door is left free to be opened to make another delivery of articles into the receptacle after the inner door has been closed but automatically locks closed from the position shown in Fig. 3 and into the position shown in Fig. 4, following the subsequent opening and closing of the outer door. When the doors are closed (see Fig. 1), the releasable fasteners 11 and 12 serve to hold them from unintentional opening.

Modifications in construction are contemplated within the spirit of my invention and within the scope of the following claim.

Having described my invention, what I claim as new and desire to secure by Letters Patent is:

A receptacle having outer and inner doors, means for releasably fastening said doors closed, and mechanism for locking said outer door in closed position, said mechanism comprising, a catch member projecting inwardly from said outer door, a latch hinged in said receptacle to swing vertically and laterally into substantially horizontal normal position for cooperative engagement with said catch when the outer door is closed, means urging said latch into said normal catch engaging position, depressible means actuated by the opening movement of said inner door for swinging said latch vertically out of the path of and out of engagement with said catch when the inner door is opened and releasing said latch to move into catch engaging position when the inner door is closed, a block slidably supported on said latch and adapted to move forwardly and close the entrance into the latch when the latter tends to swing into catch engaging position, and a spring mounted to slide said block forwardly into blocking position and permitting said block to retract under the action of said catch entering into engagement with said latch after the outer door has been opened and again closed following the closing of the inner door.

EARL W. STORMS.
